UNITED STATES PATENT OFFICE.

JOHN DONOVAN, OF BOSTON, MASSACHUSETTS.

BOOT OR SHOE STRETCHER.

SPECIFICATION forming part of Letters Patent No. 355,006, dated December 28, 1886.

Application filed June 9, 1886. Serial No. 204,567. (No model.)

To all whom it may concern:

Be it known that I, JOHN DONOVAN, of Boston, in the county of Suffolk, State of Massachusetts, have invented a certain new and useful Improvement in Lasts, of which the following is a description sufficiently full, clear, and exact to enable any person skilled in the art or science to which said invention appertains to make and use the same, reference being had to the accompanying drawings, forming part of this specification, in which—

Figure 1 is a vertical longitudinal section of my improved last, one of the toe-pieces being represented as removed and the other shown in side elevation; Fig. 2, a top or plan view of the last with both toe-pieces in position for use; Fig. 3, a vertical transverse section taken on line *a a* in Fig. 2, and Fig. 4 a side elevation of one of the toe-pieces detached.

Like letters of reference indicate corresponding parts in the different figures of the drawings.

My invention more especially relates to that class of lasts which are employed for stretching boots and shoes; and it consists in a novel construction and arrangement of the parts, as hereinafter more fully set forth and claimed, the object being to produce a more effective and otherwise desirable article of this character than is now in ordinary use.

The nature and operation of the improvement will be readily understood by all conversant with such matters from the following explanation.

In the drawings, A B represent the toe-pieces; C, the main heel-piece; E, the stretching-screw, and H the auxiliary heel-piece. The toe-pieces are hinged together at *x*, and provided at their rear ends with a nut, *m*, for the screw E. The nut *m* is journaled on trunnions *v* in the toe-pieces A B, thereby permitting it to rock and the rear end of the screw E to be raised and lowered, as occasion may require.

A threaded stud, J, projects laterally from the inner face of the toe-piece A, said stud being provided with an elongated nut, K, adapted to enter a socket, *z*, in the piece B. A plate, N, provided with an elongated slot, *t*, is fitted to slide on the inner face of the toe-piece B, said plate being kept in proper position by the screw *i*, and adapted to close the socket *z*, and

prevent the nut K from entering the same, as occasion requires.

The screw E is provided with a wheel or sette, M, to enable it to be readily turned, its rear end being journaled in a gib or step, *t*, which is fitted to slide vertically on the inner face of the heel-piece C. The auxiliary heel-piece H is larger than the piece C, and is designed to be employed in addition to the last-named piece when the last is used for stretching a large boot or shoe.

In the use of my improvement the nut K is turned onto or off the stud J, as the case may be, until the toe-pieces A B are properly adjusted, after which the last is inserted in the shoe and the screw E turned to force the toe-pieces forward until it is properly stretched.

When it is required to separate the toe-pieces to a greater extent than can be accomplished by means of a nut, K, entering the socket *z*, the plate N is moved to close said socket, thus preventing the nut from entering the same.

The heel-piece C is provided with a boss or projection, *f*, to lessen the bearing-surfaces between the heel-pieces, and also to enable the piece C to adjust itself readily to the auxiliary piece H when the outer end of the screw E is depressed. When the piece H is not used, a heel-piece, C, on which the boss *f* is omitted, may be employed.

A price-card, Q, may be inserted in the upper portion of the heel-piece C when the last is used to keep the boot or shoe in proper shape while being exhibited in a show window or case, if desired.

I do not confine myself to closing the socket *z* by means of the plate N, as other means may be employed for this purpose. Neither do I confine myself to the use of the step or gib *t*, as the same may be omitted, if desired, although I deem it preferable to use it.

Having thus explained my invention, what I claim is—

1. In a last for stretching boots and shoes, the combination of the following instrumentalities, to wit: two toe-pieces adapted to be inserted in the fore part of the boot or shoe, said toe-pieces being hinged together at their rear ends and provided with a rocking or journaled nut, a stretching screw working in said nut, a heel-piece adapted to be inserted in the heel

portion of the boot or shoe and to receive the end-thrust of said stretching-screw, said toe-pieces being provided with means for adjustably separating their free ends, substantially as described.

2. In a last for stretching boots or shoes, two toe-pieces hinged together at their rear ends, one of said toe-pieces being provided with a laterally-projecting threaded stud and a nut adapted to fit said stud, and the other with a socket adapted to receive said nut, and means for closing said socket, substantially as set forth.

3. In a stretching last for boots or shoes, the toe-piece B, provided with the socket z, and sliding plate N, in combination with the toe-piece A, provided with the stud J and nut K, substantially as described.

4. The heel-piece C, in combination with the screw E, nut m, and hinged toe-pieces A B, substantially as and for the purpose specified.

5. The heel-piece C, provided with the boss

f, to enable it to adjust itself to the auxiliary piece H when the outer end of the screw E is moved vertically, substantially as described.

6. The auxiliary heel-piece H, in combination with the heel-piece C, screw E, nut m, and hinged toe-pieces A B, substantially as set forth.

7. The improved stretching-last for boots or shoes herein described, the same consisting of the toe-piece A, provided with the stud J and nut k, the toe-piece B, provided with the socket z and sliding plate N, the screw E, provided with the gib or step t and rosette M, the heel-piece C, nut m, and hinge x, constructed, combined, and arranged to operate substantially as set forth.

JOHN DONOVAN.
